CIGARETTE TRAY OR RECEPTACLE

Sidney M. Dickson, Perrysville, Pa.

Application October 17, 1946, Serial No. 703,729

4 Claims. (Cl. 131—240)

1

My invention relates to a cigarette or ash tray or receptacle of such construction that it is fire-safe and has various other advantageous features.

Common types of ash trays for cigarettes and the like have the outstanding disadvantage of being unsafe from the standpoint of fire hazard, that is, the cigarette when laid on a ledge on the mouth portion of the ash tray would, as a result of predetermined burning of the lit end thereof, finally fall outwardly instead of inwardly in the ash tray, thereby oftentimes causing a fire. In other words, the overhanging portion of the cigarette extending outwardly from the supporting edge would become heavier or provide a greater moment arm than the inwardly projecting portion of the cigarette due to consumption or burning of a predetermined portion of such inwardly extending portion. Attempts were made to provide a fireproof structure by laying the central portion of the cigarette on the edge or mouth of the tray and rest the lit portion on a grille of some kind, sometimes making the outer edge or lip slightly higher than the top of the grille so as to incline the cigarette slightly with the thought that as the cigarette would burn it would surely fall inside the ash tray rather than the outside. However, I have found by actual tests that such mode of operation does not always follow, due to a fact which has not been hitherto known in the art, that as the lit portion burns away, instead of the ashes immediately crumbling so as to progressively drop the cigarette farther and farther into the ash tray, the ashes actually often retain their solid cylindrical contour even after burning or consumption of such lit portion of the cigarette, thereby forming a bridge forming a continuation of the unlit portion and being sufficiently strong to support such unlit portion of the cigarette so that finally such bridge becomes of such great length that the unburned portion of the cigarette projecting from the ledge into the ash tray would become much smaller than its original length and even smaller than the overhanging portion extending from the ledge outwardly of the ash tray, thereby causing the moment arm of the outwardly extending portion to become greater than that of the inwardly extending portion thereby causing dropping of the cigarette outside of the container. This would oftentimes result in a fire.

Another outstanding objection to common types of cigarette ash trays is that the ledges provided on the lip or mouth portion thereof have the outstanding objection of being unsanitary.

2

from the standpoint that the end of the cigarette moistened by the lip touches such ledges so as to make these ledges convenient means to spread disease from one smoker's mouth to that of a subsequent smoker or user of the ash tray.

A further outstanding objection of common types of ash trays is that usually the lit end of the cigarette is supported on a surface of a sufficiently large area as to cause appreciable condensation or sweating on the burning end of the cigarette, thereby giving an undesirable taste to the smoke, rendering the smoking of the burned end much less enjoyable than the consumed portion.

15. An object of my invention is to provide a novel cigarette or ash tray that is devoid of the various above-mentioned disadvantages of well-known types of trays.

A more specific object of my invention is to provide a novel fireproof cigarette tray or receptacle of such construction that it would be impossible for a cigarette placed therein to burn away and fall outside thereof so as to become a fire hazard.

20. A more specific object of my invention is to provide an ash tray that completely encloses a supported lit cigarette so that no portion of the cigarette will overhang its outer edge or lip and which has a grilled support therein on which is rested the lit end of the cigarette.

25. A further object of my invention is to provide an ash tray for cigarettes and the like which has an outwardly extending lip portion which is entirely free or devoid of ledges for laying the cigarette horizontally, and which tray provides a minimum area of support at the intermediate portion of the cigarette and at the lit end thereof so as to make it fireproof, sanitary and at the same time eliminate condensation or sweating on the lit end that might impart an undesirable flavor to the smoke.

30. A still more specific object of my invention is to provide an ash tray for cigarettes and the like having an outwardly flared lip portion extending from the mouth or opening of the tray, which flared lip portion extends beyond and encloses the moist end of the cigarette which is placed in one's mouth, and wherein the edge forming the joint between the flared lip portion and the main body of the ash tray comprises a supporting edge against which is leaned an intermediate portion of a cigarette, the other support for the lit end being in the form of a grille having spaced members either in concentric parallel form or extending radially outwardly to support the lit end on

a surface of minimum area and make the cigarette assume an inclined position so that it will be impossible to drop outside of the flared lip portion, serving as a guard or catch basin, irrespective of the extent of burning at the lit end.

Other objects and advantages of my invention will become apparent from a study of the following specification taken with the accompanying drawings wherein:

Fig. 1 is a top view of a cigarette tray or receptacle embodying the principles of my invention;

Fig. 2 is a cross-sectional view taken along line II—II of Fig. 1;

Fig. 3 is a vertical cross-sectional view of a modified form of my ash tray mounted on a smoking stand, and

Fig. 4 is a fragmentary top view with parts shown broken away of the structure shown in Fig. 4.

Referring more particularly to Figs. 1 and 2, numeral 1 denotes a cup-like receptacle or tray for collecting ashes from a deposited burning cigarette or the like, and at the top or mouth portion of which there is a cylindrical portion 2 from the top edge or mouth of which extends an outwardly flared portion 3. At the peripheral edge 4 forming the joint between flared portion 3 and cylindrical portion 2 there are provided a series of arcuate indentations or bulges that are adapted to conform somewhat to the curvature of the cigarette so as to form a plurality of pockets to prevent the cigarette from rolling along the peripheral edge 4 when leaned thereagainst. These arcuate portions may be made by hammering, pressing or expanding by dies, or by any other suitable method that is known in the metal working art.

Intermediate the cylindrical portion 2 a shoulder is formed for supporting a grille or grid 5 comprising a plurality of concentrically disposed wires, metal stampings, castings of metal, ceramic or other fireproof material having a central opening through which butts may be dropped, which grille is supported on radially extending support members 6 fastened to the walls of cylindrical portion 2 and which underlie the grille. Thus when a lit cigarette, such as 7, is placed in the ash tray or container, its intermediate portion will lean against and snugly fit within one of the curved portions of edge 4, whereas its lit end will rest upon one of the concentric elements of grille 5 and will not come in contact with any radially extending elements of support 6.

The cross-section of the grid or grille elements or sections coming in contact with the burning end of the cigarette should be kept at a minimum, say approximately $\frac{1}{16}$ of an inch in diameter in case they are made of wires, to prevent sweating or accumulation of moisture as well as to prevent piling up or accumulation of burned ash. The distance between grid sections or members for optimum operation should be slightly less than the diameter of the cigarette, that is should be spaced on approximately $\frac{1}{16}$ inch centers to prevent the cigarette from falling through the grid and into the receptacle 1 and thereby becoming contaminated with ash or collecting moisture and sweating by coming in contact with a large support area or surface. That is to say, if the spacing between grid wires were substantially less than $\frac{1}{16}$ inch, then instead of one or two of such wires to support the burned end there will be three or more which would increase the supporting area and provide a greater degree of

condensation or sweating at the burned end which would substantially impair the taste of the smoke. Thus it will be seen that by providing the grid sections in the same parallel direction and of suitable dimensions and by eliminating any crosswise extending sections on or near the surface of the grid the cigarette-supporting or contact area will be materially reduced, hence the condensation or sweating that inherently occurs at the burned end will be practically eliminated. Such grid work structure due to its large openings, of course, allows free falling of the ashes therethrough, hence the grid will remain at all times fairly clear of ashes, hence it will not be subject to substantial discoloration as is usually attendant with sweating or condensation. Only clean ashes, that is ashes devoid of moisture, condensation, etc., will fall into the cup 1, which so as not to mar the inner finished surface of the ash collector or cup-like receptacle 1.

When it is desired to empty tray 1, it is merely necessary to lift the grill 5 from its supporting shoulders 2a which can be readily done by inserting one's finger through the central opening of the grille.

It will be seen from an inspection of Fig. 2 that the deposited cigarette 7 which is laid in an inclined position will never fall outwardly of the flared portion 3 which completely encloses or surrounds it, irrespective of the mode of burning of the burned end of the cigarette. That is, even assuming that the burned end retains its solid cylindrical shape despite consumption or burning thereof and thereby provides a bridge or support of ash for the unburned portion, nevertheless, whenever such bridge portion finally does break down, the most that can happen is that the cigarette will either slide substantially axially so as to drop to a greater extent into the cylindrical portion 2 in its inclined position, or it will tip over and lie on top of the upper surface of the grid. In either event, since the lit cigarette will at all times be maintained within the confines of the cigarette container or tray, it will never constitute a fire hazard. Furthermore, the inclined position of cigarette 7 provides convenience in handling for continued smoking until the cigarette becomes too small for smoking.

Figs. 3 and 4 show a modified form of my cigarette tray or container and shows it supported in a smoking stand or support of the pedestal type. More specifically, upon pedestal 8 there is fitted a substantially hemispherical bowl portion 9 having a stepped marginal edge portion 10 for supporting the grid or grille 11 which edge portion is continued vertically upwardly to edge or mouth 12 having arcuate indentations 12a formed along the periphery thereof similar to those in edge 4 in Figures 1 and 2. From this edge there extends the outwardly flared lip portion 13 similar to flared portion 3 of Figure 2.

Instead of providing a grid 11 of concentric sections, there is shown by way of modification a grid made up of a plurality of radially extending sections or elements 11a having their outer ends secured to ring 15 and supported on the edge 10 and having inner ends secured to ring 14. The sections 11a may constitute either wires that are woven through holes in rings 14 and 15 or may be elements welded to such rings or, in fact, supported in any desirable manner. It should be understood, however, that the concentric type of grid shown in Figures 1 and 2 could be substituted for that shown in Figures 3 and 4. The essential

feature is that such elements $11a$ should be of minimum cross-section, say of the order of $\frac{1}{8}$ inch in diameter and should be spaced sufficiently close together so that the cigarette will not fall therethrough and at the same time sufficiently far apart so that one or never more than two of such sections will constitute the support for the burned end of a cigarette. This will insure minimum contact area and effectively eliminate condensation or moisture formation at the lit end of the cigarette. The general requirement for the grille sections is that they extend in the same direction and are as parallel as possible.

Within bowl portion 9 there is supported a correspondingly shaped bowl 16 for collecting the burned ashes, which bowl is readily removable for the purpose of emptying the ashes after they have accumulated for a period of time therein. A tray 17 in the form of a frustum of an inverted cone extends from ring 15 and supports a bracket 18 rigidly secured thereto and depending therefrom. At the bottom of tray 17 is a round hole or opening. The hole or opening is normally closed by disk-shaped door or gate 19 rigidly secured to a stem 20 , which stem can be turned in either direction along its axis by manipulating knob 21 . A leaf spring 22 having one end anchored to bracket 18 and the other end extending radially through a slot formed in stem 20 serves to center at all times or normally bias door 19 to its closed position. Spring clip 26 secured to the bottom of tray 17 keeps the door 19 closed tightly. The entire tray assembly including tray 17 , grid 11 and door operating mechanism is readily removable by lifting it from the supporting edge portion.

In operation when it is desired to open door or gate 19 so as to empty the container or tray 17 of its accumulated ashes, knob 21 is turned in either direction so that the gate 19 is moved horizontally to provide a sweeping or self-cleaning movement. This action prevents matches or cigarettes from catching or interfering with automatic closing of the gate and keeps the surface reasonably clean. Since leaf spring 22 normally biases or returns the open gate to its closed position, this will facilitate smothering of burning cigarettes. Thus the gate will operate with equal effectiveness in either direction and will permit the operating knob 21 and gate 19 to be returned either clockwise or counter-clockwise.

In order to prevent partially consumed cigarettes or ashes from pyramiding or piling up directly under the gate, spreaders or fingers, such as 24 , may extend from the gate so as to provide a wiping action to break up and spread the top of the pile of the ashes. If desired, one or more fingers or arms, such as 25 , rigidly secured to stem 20 may serve substantially the same purpose of breaking up and spreading the top of the ash pile to prevent clogging at the gate and increase the capacity of the bowl 16 materially. Thus either finger 24 or 25 or both of them, as shown, may be used for this purpose.

Thus it will be seen that I have provided an ash tray suitable for cigarettes and which may be designed for cigars and the like as well, and which is so constructed as to be absolutely fire-proof, and which is substantially devoid of cigarette-supporting ledges which would otherwise make it unsanitary and that includes a grid or grille which provides minimum support or contact area with the lit end of the cigarette, thereby maintaining condensation or moisture

thereat at a minimum so as not to impair the taste of the smoke from the cigarette and holds the cigarette in a desirable inclined position to handle for continued smoking until it becomes too short; furthermore, I have provided a novel cigarette tray or container, as well as a stand therefor, which is relatively inexpensive to manufacture and is capable of holding a large number of cigarettes and of accumulating a large amount of ashes and which at the same time provides a pleasing appearance and is relatively easy to keep clean.

While I have illustrated and described certain specific embodiments of my invention, it will be understood that this is by way of illustration only and that various changes and modifications may be made within the contemplation of my invention and within the scope of the following claims.

I claim:

1. A cigarette ash tray comprising a round receptacle having a substantially vertical upper wall portion, a lip integrally joined at its lower edge to the upper edge of said wall portion, said lip being curved outwardly and upwardly from its lower edge, the annular juncture of said lip and said wall portion having a plurality of concave recesses spaced equidistant thereabout, and a grid for supporting a lit end of a cigarette positioned below the upper edge of the wall portion, the curvature of said lip portion being such that when a cigarette has its lighted end supported on a portion of the grid on one side of the center thereof and with a medial portion of the cigarette supported by the lower end of the lip portion in one of the recesses on the same side of the center of the grid the portion of the cigarette above the recess will lie within the zone bounded by the lip portion, but out of contact therewith.

2. A device as claimed in claim 1 in which the grid comprises radially and downwardly extending wire-like elements providing a truncated-cone-like supporting surface for the lit end of a cigarette.

3. A cigarette supporting and ash receiving tray comprising an open mouthed receptacle portion, an upwardly and outwardly extending curved lip portion formed integrally with the upper portion of said receptacle portion, the integral juncture of said receptacle portion end of said lip portion having a plurality of concave recesses spaced equidistant thereabout, said recesses having curvatures corresponding to that of a cigarette so as to snugly seat and prevent rolling of the cigarette along the upper periphery of the receptacle portion, and a grid supported below the mouth of said receptacle to support the lit end of a cigarette when the body of the cigarette is resting in one of the aforesaid recesses, said grid comprising elongated metallic elements spaced apart a distance less than the diameter of a cigarette and an ash receiving well disposed below said grid, the curvature of said lip portion being such that when a cigarette has its lighted end supported on a portion of the grid on one side of the center thereof and with a medial portion of the cigarette supported by the lower end of the lip portion in one of the recesses on the same side of the center of the grid the portion of the cigarette above the recess will lie within the zone bounded by the lip portion, but out of contact therewith.

4. An ash tray for cigarettes and the like com-

prising a receptacle having a base and side walls projecting vertically upwardly from the peripheral edges thereof, the uppermost end of said side walls providing a ledge for supporting engagement with the medial portion of a cigarette having its lighted end resting against said base, and a protector rim extending upwardly and outwardly from said ledge, the surface formation of said rim being such that when a cigarette has its lighted end supported on a portion of the base on one side of the center thereof and with a medial portion of the cigarette supported by the ledge on the same side of the center of the base, the portion of the cigarette above the lower end of the rim will lie within the zone bounded by the rim, but out of contact therewith.

SIDNEY M. DICKSON.
